UNITED STATES PATENT OFFICE.

CASIMIR ZEGLEN, OF CHICAGO, ILLINOIS.

BULLET-PROOF FABRIC.

SPECIFICATION forming part of Letters Patent No. 578,000, dated March 2, 1897.

Original application filed April 24, 1896, Serial No. 588,874. Divided and this application filed June 8, 1896. Serial No. 594,667. (No specimens.)

To all whom it may concern:

Be it known that I, CASIMIR ZEGLEN, of Chicago, in the county of Cook and State of Illinois, have invented certain new and useful Improvements in Bullet-Proof Fabrics; and I do hereby declare that the following is a full, clear, and exact description thereof, reference being had to the accompanying drawing, and to the letters of reference marked thereon, 5 which forms a part of this specification.

This invention relates to bullet - proof shields, and more especially to an improved composite elastic fabric adapted to resist penetration of projectiles by cushioning or 15 absorbing the impact of the same.

The object of the invention is to provide a relatively light and more or less flexible fabric which may be worn without serious inconvenience to protect the body of a person and 20 which may also be used for various other analogous purposes.

This application is a division of an application, Serial No. 588,874, filed by me April 24, 1896.

The invention consists in the matters hereinafter described, and more particularly pointed out in the appended claim. It will be readily comprehended by reference to the accompanying drawing.

The figure of the drawing represents in a perspective view a section of the fabric constructed in accordance with my invention.

Referring to the drawing, A designates the outermost layer of the fabric or that against which the projectile strikes, said outer layer or covering consisting of two or more plies or thicknesses of a closely - woven relatively heavy strong fabric, such, for example, as canvas. After experimentation I have ascertained that the most satisfactory results are obtained by making this outer covering of linen canvas of a quality commonly known as "Aberdeen" canvas, and hence while I recommend the same I do not desire to be limited thereto.

Next inside of the canvas cover A, I provide a layer B of fine strong animal hair, which is either naturally straight or which may be combed so that the fibers thereof lie 45 substantially parallel with each other and

thus very compactly. This layer B is relatively a thick layer, as shown, and may be composed of various kinds of hair. I have obtained the best results, however, by the use of the hair or what is more commonly called the "wool" of the Angora goat, the hair of this animal having the desirable characteristics of strength, straightness, and fineness of staple and being, therefore; susceptible of being formed into a very compact mass.

Next to the layer of hair B, I provide a plurality of layers of strong flexible cords, threads, or strands C C', the cords or strands of each layer being laid side by side or parallel with each other and directly in contact with each other. The several layers C C' of parallel-arranged strands are superposed one upon each other in such position that the several strands of one will lie in a direction transversely to or diagonally to the direction of the strands of the other layer, that is, at an angle to each other, as clearly shown in the drawing. In practice I have found that these woven inner layers are best constructed of silk cord, which, owing to the fineness of the fiber and its relatively great strength and also, doubtless, to the peculiar characteristics of silk, afford the most satisfactory results, although I do not desire to be limited thereto.

The several layers thus formed are arranged, as shown, very compactly and are secured together, preferably, by through-and-through stitching with silk thread, as indicated at a a, so that the whole becomes a relatively hard exceedingly compact mass having peculiar characteristics.

The composite fabric thus formed I may make into jackets or shields, since it possesses sufficient flexibility for that purpose and is of such weight as to permit it to be worn without serious discomfort. Preferably when the fabric is made into jackets, shields, or other forms of wearing-apparel it will be covered or lined with any suitable cloth, in order that it may have a more presentable appearance, but as this is obviously a non-essential feature I have not seen fit to illustrate it.

The fabric thus constructed is adapted to successfully resist the penetration of projectiles, such as bullets fired from ordinary re-

volvers or other small arms, successfully cushioning the impact of the bullet to prevent any injury to the wearer of the shield or jacket.

I claim as my invention—

5. A bullet-proof fabric consisting of an outer covering of canvas, a layer of unwoven hair or wool, and a plurality of inner layers, each composed of strong strands or cords laid side by side compactly together, the cords of the different layers being arranged at an angle to each other, the whole fabric being com-

pactly bound together by stitching, substantially as described.

In testimony that I claim the foregoing as my invention I affix my signature, in presence of two witnesses, this 14th day of August, A. D. 1896.

CASIMIR ZEGLEN.
